UNITED STATES PATENT OFFICE.

WINCESLAS B. HOBERT, JR., OF JACKSON, MISSISSIPPI.

SWIMMING APPLIANCE.

Application filed December 15, 1921. Serial No. 522,599.

To all whom it may concern:

Be it known that I, WINCESLAS B. HOBERT, Jr., a citizen of the United States, residing at Jackson, in the county of Hinds and 5 State of Mississippi, have invented certain new and useful Improvements in Swimming Appliances, of which the following is a specification.

This invention relates to swimming appliances and has as its general object to 10 provide a device which may be readily and conveniently applied to the person and worn with comfort and which, while inconspicuous, will serve effectually to buoy the wearer 15 in the water for an indefinite period of time.

One of the most specific objects of the invention is to so construct the device that the 20 same will be proof against leakage of air with which it is inflated and will not be liable to become distorted or displaced while 25 in use.

Another object of the invention is to so 30 construct the appliance that it will be effectually re-enforced without, however, the provision of any extraneous means for obtaining this result.

In the accompanying drawings:

Figure 1 is a perspective view of the 35 appliance in use,

Figure 2 is a front elevation of the 40 appliance removed,

Figure 3 is a detail vertical front to rear 45 sectional view taken substantially on the line 3—3 of Figure 2 looking in the direction indicated by the arrows,

Figure 4 is a horizontal sectional view 50 taken substantially on the line 4—4 of Figure 2 looking in the direction indicated by the arrows.

The appliance embodying the invention 55 comprises a closed body which is indicated in general by the numeral 1 and which is preferably made of rubberized cloth or any similar material which is impervious to water and which possesses the required degree of 60 strength, the material named, however, being found preferable for the purpose. The body 1 comprises walls 2 and 3 which are preferably of corresponding marginal contour and substantially rectangular, and these walls are cemented or otherwise united to each other along their marginal portions as indicated by the numeral 4 so that the body is completely closed on all sides. Besides 65 being mutually united at their marginal por-

tions, the walls 2 and 3 of the body are united, by cementing or otherwise, along a vertical line parallel to the lateral edges of the body and spaced midway between said edges, as indicated by the numeral 5. The line of union 5 therefore extends vertically of the body but it terminates short of the upper and lower edges of the said body so that as a consequence the body is divided into two laterally disposed air pockets 6 placed in communication with each other by passage ways 7 and 8 located respectively at top and bottom of the body. In order that the body may be inflated when it is desired to use the appliance, a suitable inflating valve 9 is arranged in the wall 3 of the body above the upper end of the seam 5 and it will be evident that air introduced into the body by way of this valve will enter the passage way 7 and be distributed to the 70 pocket 6, filling also the passage way 8. Thus both of the pockets are designed to be inflated by way of the single inflating valve 9 and while the pockets are in a sense separate from one another, they are suitably 75 placed in communication with each other by way of the passage ways 7 and 8. Because of the provision of the vertical seam 5 at the middle of the body, the body is in a 80 sense divided at its vertical middle so that it may be more readily flexed and will thus more readily accommodate itself to the movements of the body when it is applied thereto. In other words, the two halves of the body, 85 so to speak, may have relative movement about the seam 5 but such movement would not be permitted to the same extent if the walls of the body were not connected at the vertical middle thereof as by the said seam.

The appliance is intended to be worn upon 90 the chest, and in order that it may be securely held in place when applied, adjustable straps 10 are connected each at one end to the body at one side thereof and near the upper and lower corners as indicated by 95 the numeral 11, and these straps are provided with fastening elements 12 engageable with other fastening elements 13 which are secured upon flaps 14 provided at corresponding points at the opposite edge of 100 the body. It will now be evident that when the device is inflated and applied to the body as illustrated in Figure 1 of the drawings, it will serve effectually as a means for buoying 105 the person to whom it is applied and, being 110

of material impervious to water, will sustain the person in the water for an indefinite period of time.

It will be understood that while the appliance is intended primarily for use in swimming or as a life preserver, it may be put to various other uses such for example as a cushion, ice-water bag, hot-water bag, etc.

Having thus described the invention, what is claimed as new is:

In a swimming appliance, an inflatable member for disposal against the abdomen and comprising walls marginally united and also united along the vertical median line of the member whereby to provide two air pockets located a single one at each side of said median line and presenting a smooth and unbroken surface throughout the height of the appliance, the air pockets being in

communication with each other, means whereby air may be introduced into one of said pockets to inflate both said pockets, a strap connected to one upper corner of the member and adapted to be passed about the body in a line immediately below the arm pits, means for connecting the strap to the opposite upper corner of the member, a strap connected to one side of the member above one lower corner thereof and in position to extend about the waist line, and means for connecting the last mentioned strap to the opposite side of the member at a correspondingly located point, the air pockets extending below the line of circumferential extent of the last mentioned strap.

In testimony whereof I affix my signature.

WINCESLAS B. HOBERT, JR. [L. S.]
